DESIGN FOR A RADIO TUBE SHIELD

Frederick Hafecost and Edward F. Staver, Brooklyn, N. Y., assignors to Goat Radio Tube Parts, Inc., Brooklyn, N. Y., a corporation of New York

Application June 1, 1938, Serial No. 77,496

Term of patent 7 years

To all whom it may concern:

Be it known that we, Frederick Hafecost and Edward F. Staver, citizens of the United States and residents of Brooklyn, county of Kings, and State of New York, have invented a new, original, and ornamental Design for a Radio Tube Shield, of which the following is a specification, reference being had to the accompanying drawing, forming a part thereof, wherein:

Fig. 1 is a front elevation of a tube shield embodying our new design;

Fig. 2 is a side elevation thereof.

Fig. 3 is a top plan view of the shield, with the shield orientated as in Fig. 1; and

Fig. 4 is a bottom plan view of the lower half of the shield, with the shield orientated as in Fig. 2.

We claim:

The ornamental design for a radio tube shield, substantially as shown.

FREDERICK HAFECOST.
EDWARD F. STAVER.
